EP 1067086 A2 1/2001

Primary Examiner — George A Bugg

Assistant Examiner — Tamara L Hahn

(74) Attorney, Agent, or Firm — Schwabe Williamson & Wyatt

(57) **CLAIM**

We claim the ornamental design for a counterbalance forklift truck, as shown and described.

DESCRIPTION

FIG. 1 is a front perspective view showing my design;

FIG. 2 is a rear perspective view;

FIG. 3 is a front view;

FIG. 4 is a rear view;

FIG. 5 is a left side view;

FIG. 6 is a right side view;

FIG. 7 is a top view; and,

FIG. 8 is a bottom view.

Broken lines in the figures form no part of the claimed design.

1 Claim, 8 Drawing Sheets(56)
